UNITED STATES PATENT OFFICE.

FRIEDRICH TRÄBERT, OF RATHENOW, GERMANY.

CENTERING.

SPECIFICATION forming part of Letters Patent No. 431,628, dated July 8, 1890.

Application filed September 23, 1889. Serial No. 324,863. (No model.)

To all whom it may concern:

Be it known that I, FRIEDRICH TRÄBERT, a subject of the German Emperor, residing at Rathenow, in Germany, have invented a new 5 and useful Improvement in Centering, of which the following is a specification.

This invention relates to adjustable centering, and is represented in the annexed drawings in Figures. 1 to 4. The centering is adjustable and the pitch regulated automatically.

Figs. 1 and 2 show centers completely drawn together in side view and plain view. Fig. 3 represents the same center partly drawn out 15 in side view, and Fig. 4 is a view of the partly-drawn-out center with vault removed.

The centering consists of the vault-rails c c^2 and of the tie-rails b b^2 , which are journaled at their ends into a pair of cheeks d d' 20 and d' d' . The tie-rails b b^2 are securely riveted to the cheeks d d' , and the guides b' and b^3 on the inner ends of these rails are so arranged that the guide b' grasps the rail b^2 , and the guide b^3 does likewise with the rail 25 b , Figs. 1, 3, and 4. The rail b^2 has holes at certain intervals, and the rail b is likewise provided at a^2 with a hole for inserting a pin r^2 , attached to b^2 , through a^2 and into a corresponding hole at b^2 , according to the span required. The outer ends of the vault-rails c 30 and c^2 rest on and between the cheek-pins d and d' and are secured at a by pin r and at a' by pin r' . Instead of the pins, screws may be used for securing the vault-rails between 35 the cheeks, in which case the holes should be provided with corresponding worms. The guides existing at the inner end of the vault-rails are so arranged that the guide c' of the rail c grasps the vault-rail c^2 , and the guide c^3 40 of the vault c^2 holds the vault-rail c , Figs. 1 to 3. The spikes s' and s , arranged at the

vault-rails c and c^2 , are for the correct erection of the centering-pieces and serve for holding them together. The cheek-pairs d and d' are provided at the upper ends with projecting flaps e and e' , which rest upon the abutments of the girders. 45

The use of the described centering is as follows: After the pin r' has been withdrawn from the rails b and b^2 the centers are adjusted for the correct span of arch by shifting the rails b and b^2 and c and c^2 , respectively, and are then fixed by the pin r^2 , which is inserted through the hole a^2 of the rail b and through the corresponding hole of the rail b^2 , when the pitch regulates itself automatically in the proportion of twelve to one as the vault-rails c and c^2 are movable on the pins r' , Fig. 1, and screws r' , Fig. 3, and when, for instance, an arch is to be executed between iron supports, the vault-centers with their flaps e e' and e' e are suspended at the flanges of the iron girders and are adjusted by the plummet, and the connection of the centers between themselves is effected by two lathes L , which 55 are driven into the spikes s' and s , fixed on the rails c and c^2 . The lathes, which are further necessary, are equally distributed over the arches. 60

I claim—

The adjustable bearers c c^2 , with their spikes s' s , and the tie-rails b b^2 , with their jaws b^3 b' , together with the cheeks d d' and d' d' , all substantially as illustrated and described, for the purposes set forth. 70

In testimony whereof I have signed this specification in presence of two subscribing witnesses.

FRIEDRICH TRÄBERT.

Witnesses:

JULIUS MAASS,
HERMANN BRANDT.
